MEANS FOR LUBRICATING A DEEP
WELL PUMPJames M. Hait, Los Angeles, Calif., assignor to
Food Machinery Corporation, a corporation of
Delaware

Application April 29, 1935, Serial No. 18,821

11 Claims. (Cl. 184—6)

This invention has to do in a general way with turbine pumps such as are used in pumping water wells for domestic and industrial purposes and is more particularly related to improvements of the general character disclosed in my co-pending application Serial No. 743,562, wherein the lubricant employed in lubricating the line shaft bearings of a pump of this type is so controlled that it does not enter either the well water or the water being pumped whereby contamination of the water is eliminated.

The present invention has as a general objective the provision of a lubricating system of the class described wherein the lubricant may be delivered into the line shaft enclosing tubing by the so-called "drip method" and is withdrawn or carried from the enclosing tubing and is raised to the surface of the ground from time to time before it has an opportunity to reach the water being pumped or the water of the well.

It is one object of this invention to produce a device of the class described wherein a lubricant retaining chamber, or a lubricant accumulating reservoir, is formed in the bottom portion of the enclosing tubing itself and is associated with means whereby a pressure fluid can be delivered into such reservoir, thereby forcing the lubricant which has accumulated therein to the surface of the ground.

It is a feature of one preferred form of my invention that the lubricant retaining reservoir is divided by an upwardly extending partition so as to form a lubricant separating chamber which communicates with the lower end portion of the shaft enclosing tubing at the lower end of the separating chamber. In this form of my invention the pressure fluid is delivered into the separating chamber and the return pipe is connected to the upper end thereof.

It is a further object of this invention to provide an improved form of discharge manifold adapted to connect the bowl assembly with the delivery pipe, such manifold having connections therein whereby a pressure fluid line and a lubricant return line can be connected into the bottom portion of the lubricant retaining chamber.

It is a further object of this invention to produce a lubricant return system of the class described which is of simple form and construction and may be easily and economically installed upon standard types of deep well turbine pumps.

The details in the construction of certain

preferred forms of my invention, together with other objects attending its production, will be best understood from the following description of the accompanying drawings, which are chosen for illustrative purposes only, and in which

Fig. 1 is an elevational view with parts broken away showing a pump assembly equipped with one embodiment of my invention;

Fig. 2 is a fragmentary sectional elevation illustrating the details in the construction of the lubricant retaining chamber and its associated parts;

Fig. 3 is a plan section taken in a plane represented by the line 3—3 of Fig. 2;

Fig. 4 is a plan section taken in a plane represented by the line 4—4 of Fig. 2;

Fig. 5 is a fragmentary sectional elevation similar to Fig. 2 but showing a modified form of the invention;

Fig. 6 is a sectional elevation illustrating the details in the construction of another modified form of my invention; and

Fig. 7 is a sectional elevation illustrating still another manner in which the invention may be modified.

Referring now to Figs 1 to 4, inclusive of the drawings, numeral 11 indicates a discharge fitting which is shown as supporting a motor drive 12 and as having a surface discharge pipe 13 which is equipped with a valve 14. The discharge fitting 12 supports a delivery pipe 16 which extends downwardly into the well 17 and carries a bowl assembly 18 at its lower end, such bowl assembly being connected to the delivery pipe 16 through the medium of a bowl discharge manifold 19. The bowl assembly may be of any conventional construction having impellers (not shown) which are driven by a line shaft 21, such line shaft extending through a top bearing 22 in the manifold 19 and a shaft enclosing tubing 23 which contains line shaft bearings 24, the upper end of the line shaft extending through a suitable fitting 25 and into the driving mechanism 12 where it is secured to a rotor element.

During the operation of the pump, lubricant is delivered into the fitting 25 from any suitable source, such as a conventional drip valve, not shown, through a lubricant supply pipe 30. This lubricant flows downwardly within the enclosing tubing 23, lubricating the various line shaft bearings 24, until it finally reaches the lower end portion of the tubing 23. The manifold 19 is shown as being provided with by-pass ports 31 which communicate with the water of the well outside of the pumping mechanism. In this way

any leakage which takes place through the bearings 24, and which is under the pump pressure, is not delivered into the shaft enclosing tubing but is delivered into the well, so that the static head in the shaft enclosing tubing is the same as the static head in the well.

Through this arrangement it will be seen that as the oil accumulates in the tubing 23 it will eventually reach a height where the column of oil counter-balances the column of water surrounding the pump assembly or, in other words, the accumulated oil counter-balances the static head of the well. When this point is reached the lower end of the oil column will fall substantially at the bottom of the shaft enclosing tubing and under normal circumstances this oil, as additional oil flows down from the top of the tubing, seeps downwardly through the line shaft bearing 24' and is carried by the water leakage 20 through the bearing 22 into the well.

It is the general object of this invention to force the oil, which accumulates at the bottom of the shaft enclosing tubing, to the surface of the ground from time to time and thereby prevent 25 the bottom of the column of oil reaching a point where it can be carried out into the well. In this form of my invention I accomplish this by providing the shaft enclosing tubing with a series 30 of ports 33 which are situated at a suitable distance above the by-pass ports 31 or above the lower end portion of the shaft enclosing tubing, these ports being in communication with what I may term a separating chamber 35 which is 35 formed by surrounding the shaft enclosing tubing with a shell, such shell being secured at its ends 36 and 36' to the shaft enclosing tubing so as to form an enclosed chamber which extends a substantial distance above the ports 33.

For the purpose of intermittently purging this 40 chamber of its contents of lubricant I provide what may be termed a lubricant return pipe 38 which connects into the top portion of the chamber 35, such pipe being effective to return the lubricant from the chamber to the surface of 45 the ground when pressure is applied to the interior of the chamber. For the purpose of applying the pressure to the interior of the chamber in this form of my invention, I employ what I have termed a pressure pipe 39, such pipe being 50 shown as extending through the top portion 36' of the chamber 35 and having its lower end situated near the bottom portion thereof. The upper end of this pipe 39 is shown as being connected through a valve 40 with the surface 55 discharge pipe 13. When it is desired to purge the chamber it is only necessary to open the valve 40 and, if additional pressure is desired, the valve 14 may be partially closed so as to effect a quick and efficient purging operation.

60 In the form of my invention shown in Fig. 5, the lower end of the shaft enclosing tubing 23a is shown as being enlarged or provided with an enlarged portion 45 which constitutes the oil accumulating chamber or reservoir at the bottom 65 of the shaft enclosing tubing. It will be noted that in this form of my invention I show the discharge manifold 19a as being provided with a vertical annular wall portion 46 to which the lower end of the enlargement 45 is secured. It will also be observed that the manifold 19a is provided with a by-pass port 31a. In this 70 form of my invention it will further be observed that the manifold 19a is provided with a pressure pipe inlet connection 47 and an oil return

75 pipe outlet connection 48, the connection 47 being in communication with the pressure pipe 39a and the connection 48 being in communication with the lubricant return pipe 38a. It is preferable that the lubricant return pipe have its 80 inlet in the upper portion of the accumulating chamber or reservoir 45 and, in order to obtain this, I show the inner end of the connection as being connected to a vertically extending pipe 50 which has its open upper end situated 85 near the upper end portion of the accumulating reservoir 45.

In the form of my invention shown in Fig. 6 I propose to use the shaft enclosing tubing itself 90 as the conduit through which the lubricant is returned to the surface of the ground. In this form of my invention those parts which correspond to the elements previously described in connection with Figs. 1 and 5 are indicated by the same reference numerals distinguished by 95 the letter "b". The manifold 19b, having a by-pass outlet 31b, is similar in its general construction to the manifold 19a except that it has only one connection 47b whereby the pressure fluid is delivered into the accumulating reservoir 100 45b. In order to permit a rapid return of liquid from the accumulating reservoir 45b to the surface of the ground through the shaft enclosing tubing 23, it is necessary to provide the line shaft bearings 24b with passages or channels 50' 105 which will afford a passage through each line shaft bearing of substantially the same cross sectional areas as the stream which enters the reservoir through the pressure pipe 47b. Lubricant is adapted to be delivered into the upper 110 end of the enclosing tubing through the fitting 25b by means of a feed conduit 30b. The liquid which is carried upwardly through the enclosing tubing 23b by the application of pressure within the retaining chamber 45b is discharged through 115 a lubricant discharge pipe 51b preferably situated at the surface of the ground.

In the form of my invention shown in Fig. 7, I show the lubricant retaining reservoir 45c as being formed in the lower portion of the shaft 45 enclosing tubing 23c. This reservoir 45c is shown as being situated between two line shaft bearings 24c and 24c' and the discharge manifold 19c is shown as having a vertically extending projection 52 which receives the line shaft bearing 24c 120 to which the lower end of the tubing 23c is in threaded engagement. For the purpose of purging the chamber which is formed in the lower end of the tubing 23c, I provide a pressure line 39c, which is connected into the tubing at the 125 bottom portion of the chamber 45c, and a lubricant return line 38c which is connected into the line shaft enclosing tubing near the upper end portion of the reservoir 45c. In this form of my invention, like those shown in Figs. 2 and 130 5, the clearance between the line shaft and the line shaft bearings is so small, as compared with the passage through the lubricant return pipe, that the application of excessive pressure to the interior of the lubricant retaining reservoir is 135 effective to force the contents of the reservoir upwardly to the surface of the ground through the return pipe without materially changing the level of the liquid in the enclosing tubing above the line shaft bearing which is situated at the 140 top of the retaining reservoir. In other words, my invention contemplates the use of materially increased pressure to purge the chamber, and in these particular forms of the invention the line shaft bearings prevent the level of liquid in the 145

enclosing tubing being raised during this purging operation.

It is to be understood that, while I have herein described and illustrated certain preferred forms of my invention, the invention is not limited to the precise construction described above but includes within its scope whatever changes fairly come within the spirit of the appended claims.

I claim as my invention:

1. In combination with a vertical well pump having a bowl assembly, a line shaft, and a shaft enclosing tubing: means for delivering lubricant into the top of said enclosing tubing; a lubricant retaining chamber situated at the bottom portion of said enclosing tubing and in open communication therewith for accumulating a substantially static body of lubricant therein, and conduit means separate from said enclosing tubing for delivering pressure fluid into the bottom portion of said retaining chamber to force lubricant contained therein to the surface of the ground.

2. In combination with a vertical well pump having a bowl assembly, a line shaft, and a shaft enclosing tubing: means for delivering lubricant into the top of said enclosing tubing; a lubricant retaining chamber in the bottom portion of said enclosing tubing for accumulating a substantially static body of lubricant therein, and means separate from said enclosing tubing for delivering pressure fluid into the bottom portion of said enclosing tubing to force lubricant contained therein upwardly through said enclosing tubing to the surface of the ground.

3. In combination with a vertical well pump having a bowl assembly, a line shaft, a shaft enclosing tubing and spaced line shaft bearings in said enclosing tubing: means for delivering lubricant into the top of said enclosing tubing; a lubricant retaining chamber in the bottom portion of said enclosing tubing for accumulating a substantially static body of lubricant therein; and means separate from said enclosing tubing for applying fluid pressure within the bottom portion of said enclosing tubing to force the liquid therein upwardly through said enclosing tubing to the surface of the ground, said line shaft bearings having passages therethrough to permit the said return flow of said lubricant.

4. In combination with a vertical well pump having a bowl assembly, a line shaft, and a shaft enclosing tubing: means for delivering lubricant into the top of said enclosing tubing; means comprising an enlarged chamber for accumulating a substantially static body of lubricant in the bottom portion of said enclosing tubing during the operation of said line shaft; and conduit means separate from said enclosing tubing for delivering pressure fluid into the bottom portion of said enclosing tubing to force lubricant contained therein to the surface of the ground.

5. In combination with a vertical well pump having a bowl assembly, a line shaft, and a shaft enclosing tubing: means for delivering lubricant into the top of said enclosing tubing; a lubricant retaining chamber in the bottom portion of said enclosing tubing for accumulating a substantially static body of lubricant from said enclosing tubing during the operation of said line shaft; a lubricant return conduit having an inlet opening in the top of said retaining chamber; and conduit means separate from said enclosing tubing for delivering a pressure fluid into the said retaining chamber to force lubricant

contained therein through said return conduit to the surface of the ground.

6. In combination with a vertical well pump having a bowl assembly, a line shaft and a shaft enclosing tubing: means for delivering lubricant into the top of said enclosing tubing; a lubricant retaining chamber of greater cross-sectional area than said enclosing tubing situated in the bottom portion of said enclosing tubing for accumulating a substantially static body of lubricant from said enclosing tubing during the operation of said line shaft; a lubricant return conduit having an inlet opening in the top of said retaining chamber; and means operable independently of said enclosing tubing for delivering a pressure fluid into the bottom portion of said retaining chamber to force lubricant contained therein through said return conduit to the surface of the ground.

7. In combination with a vertical well pump having a bowl assembly, a line shaft, and a shaft enclosing tubing: means for delivering lubricant into the top of said enclosing tubing; a lubricant retaining chamber situated at the bottom portion of said enclosing tubing; a lubricant return conduit having an inlet opening in the top of said retaining chamber; and means for delivering a pressure fluid into the bottom portion of said retaining chamber to force lubricant contained therein through said return conduit to the surface of the ground, said shaft enclosing tubing extending downwardly through said retaining chamber and having a wall port communicating with the bottom portion of said retaining chamber.

8. In combination with a vertical well pump having a bowl assembly, a line shaft, and a shaft enclosing tubing: means for delivering lubricant into the top of said enclosing tubing; a lubricant retaining chamber of greater cross-sectional area than said enclosing tubing situated at the bottom portion of said enclosing tubing; a lubricant return conduit having an inlet opening in the top of said retaining chamber; and means for delivering a pressure fluid into said retaining chamber to force lubricant contained therein through said return conduit to the surface of the ground, said shaft enclosing tubing extending downwardly through said retaining chamber and having a wall port communicating with the bottom portion of said retaining chamber.

9. In combination with a vertical well pump having a bowl assembly, a line shaft, and a shaft enclosing tubing: means for delivering lubricant into the top portion of said enclosing tubing; a shell mounted on the bottom portion of said enclosing tubing and forming an annular lubricant retaining chamber surrounding said tubing, said tubing having a port therein communicating with the bottom portion of said retaining chamber; a return pipe communicating with the top portion of said retaining chamber; and conduit means for delivering pressure fluid into said retaining chamber to force liquid from said chamber through said return pipe.

10. In combination with a vertical well turbine pump having a bowl assembly, a delivery pipe, a line shaft and a shaft enclosing tubing; a discharge manifold interposed between said bowl assembly and said delivery pipe; a lubricant retaining chamber formed in the bottom of said tubing above said discharge manifold; an oil return conduit comprising a pipe extending downwardly outside of said delivery pipe, a con-

nection extending through the wall of said discharge manifold into said retaining chamber, and a vertical leg on the inner end of said last named connection having an inlet opening in the top portion of said retaining chamber; and means for delivering pressure fluid into said retaining chamber.

11. In combination with a vertical well turbine pump having a bowl assembly, a delivery pipe, a line shaft, and a shaft enclosing tubing: a discharge manifold interposed between said bowl assembly and said delivery pipe; a lubricant retaining chamber formed in the bottom of said tubing above said discharge manifold; an

oil return conduit comprising a pipe extending downwardly outside of said delivery pipe, a connection extending through the wall of said discharge manifold into said retaining chamber, and a vertical leg on the inner end of said last named connection having an inlet opening in the top portion of said retaining chamber; and means for applying fluid pressure in said retaining chamber, said last mentioned means comprising a second connection extending through said manifold and opening into said chamber and a pressure pipe communicating with the outer end of said second connection. 5 10

JAMES M. HAIT.
